UNITED STATES PATENT OFFICE.

MAXIMILIAN CHARLES SCHWEINERT, OF NEW YORK, N. Y.

DUST CAP.

Application filed April 12, 1920, Serial No. 373,539. Renewed April 23, 1922. Serial No. 557,175.

To all whom it may concern:

Be it known that I, MAXIMILIAN CHARLES SCHWEINERT, a citizen of the United States of America, residing in borough of Manhattan, city, county, and State of New York, have invented certain new and useful Improvements in Dust Caps, of which the following is a specification.

This invention relates to dust caps for tire valves, and aims to provide certain improvements therein.

In the application of Henry P. Kraft, filed September 20, 1919, Serial No. 325,097, there is shown and described a quick acting dust cap adapted to be slipped over the valve stem and turned slightly to bring into action a clamping device which is therein shown in the form of a circular member or ring with means for shortening it circumferentially to cause it to engage the valve casing and in his application filed July 17, 1919, Serial No. 311,459, there is shown and described a quick acting dust cap adapted to be slipped over the valve stem and yieldingly engage the threads thereof to frictionally hold the cap thereon. According to the present invention I provide a dust cap embodying the combination of these two types of dust caps and therefore possesses the advantages of each and the advantages resulting from their cooperation.

Referring to the drawings, which illustrate one form of the invention,—

Figure 1 is an elevation of the cap complete.

Fig. 2 is a diametrical section on an enlarged scale showing the cap applied to a tire valve.

Fig. 3 is a similar section of the foot portion detached from the tire valve.

Fig. 4 is a view similar to Fig. 3, showing the clamp released.

Fig. 5 is a bottom plan view of Fig. 1.

Fig. 6 is an elevation of the cap portion removed.

Fig. 7 is a cross-section on the line 7—7 of Fig. 2.

Fig. 8 is a cross section on the line 8—8 in Fig. 2.

Fig. 9 is an underside view of Fig. 6.

Referring to the drawings, let A indicate the cap as a whole which is shown as a dust cap for tire valves, although the invention may be applied to other articles, if desired.

B indicates the cap portion and C the foot portion, which as shown are threaded to-

gether at D. Between the two is located a clamping ring F which may be formed in one or more pieces, that shown being formed in two pieces (see Fig. 8). The foot portion 60 is preferably provided with a tapered surface G, on which the clamping ring rests, and the cap portion is preferably provided with a surrounding surface H, so that when the cap portion is screwed downwardly, the 65 ring is contracted circumferentially and binds the threads of the valve casing. To prevent the foot portion from turning, it is best formed with flats I (see Fig. 5).

As thus far described, the cap is essentially that shown in the application of Kraft before referred to.

According to the present invention I provide means for holding the cap in place, irrespective of the operation of the clamping member. Such means may be variously constructed, but I prefer that shown, wherein there is provided a spring ring J (see Fig. 7), the ends of which are turned inwardly, as shown at K K, so that they engage between the threads. The construction is such that the ends K K will pass over the threads if sufficient force is applied in either direction, so that the cap may be slid into position on the valve, or removed therefrom. 80 The ring J, however, has sufficient hold upon the valve to prevent accidental displacement.

Preferably the ring J is held in a recess L formed in the lower part of the cap member above the flange H. A portion of this 90 flange is cut away, as shown at M (Figs. 6 and 9), so as to permit the ends K K to be bent inwardly for engagement with the threads of the valve.

In the use of the cap, the latter is slid 95 over the valve casing, and when the rim nut is reached, the cap portion is rotated relatively to the foot portion, thus operating the clamping ring and positively holding the cap on the valve casing. Should 100 the user, however, neglect to turn the cap after the same is placed upon the valve, the frictional catch member will hold the cap on sufficiently to prevent its loss.

The invention is applicable to other devices than dust caps, where it is desired to fasten a cap or similar member onto a projecting part.

While I have shown and described one form of the invention, it will be understood 110 that I do not wish to be limited thereto, since various changes may be made therein

without departing from the spirit of the invention.

What I claim is:—

1. In a dust cap or the like, the combination of means for positively clamping the cap upon a tire valve or the like, and a separate frictional means for engaging the tire valve, said frictional means being adapted to permit the cap to be slid on and off the valve.
2. In a dust cap or the like, the combination of means for positively clamping the cap upon a tire valve or the like, and a separate frictional means for engaging the tire valve, said frictional means being

adapted to permit the cap to be slid on and off the valve, and said frictional means comprising a ring-shaped member adapted to yieldingly engage the tire valve casing.

3. In a dust cap for tire valves or the like, the combination of a cap portion, a foot portion, a ring-shaped clamping member adapted to be circumferentially shortened by a relative movement of the cap portion and foot portion, and a ring-shaped catch adapted to yieldingly engage a valve casing or the like.

In witness whereof, I have hereunto signed my name.

MAXIMILIAN CHARLES SCHWEINERT.
